CLAIM

The ornamental design for a gaming headset, as shown and described.

DESCRIPTION

FIG. 1 is a perspective view of the gaming headset in accordance with the present invention;

FIG. 2 is a back view of the embodiment of the gaming headset depicted in FIG. 1;

FIG. 3 is a bottom side view of the embodiment of the gaming headset depicted in FIG. 1;

FIG. 4 is a front side view of the embodiment of the gaming headset depicted in FIG. 1;

FIG. 5 is a left view of the embodiment of the gaming headset depicted in FIG. 1;

FIG. 6 is a right view of the embodiment of the gaming headset depicted in FIG. 1; and,

FIG. 7 is a top view of the embodiment of the gaming headset depicted in FIG. 1.

The broken lines form no part of the claimed design.

1 Claim, 7 Drawing Sheets
